The ornamental design for a centrifuge bottle handle, as shown and described.

DESCRIPTION

FIG. 1 is an isometric view of a centrifuge bottle handle showing my new design;

FIG. 2 is a front elevation view of the centrifuge bottle handle of FIG. 1, the rear view being identical thereto;

FIG. 3 is a side elevation view of the centrifuge bottle handle of FIG. 1, the other side view being identical thereto;

FIG. 4 is a top elevation view of the centrifuge bottle handle of FIG. 1; and,

FIG. 5 is a bottom elevation view of the centrifuge bottle handle of FIG. 1.

The broken lines shown in FIG. 1 depict environmental structure that forms no part of the claimed design. The broken lines in FIG. 5 enclose an unclaimed portion of the design, and also form no part of the claimed design.
